S. TAGGART.

Mill Bolt.

No. 12,422.

Patented Feb. 20, 1855.

UNITED STATES PATENT OFFICE.

SAMUEL TAGGART, OF INDIANAPOLIS, INDIANA.

FEEDING FLOUR-BOLTS.

Specification of Letters Patent No. 12,422, dated February 20, 1855.

To all whom it may concern:

Be it known that I, SAMUEL TAGGART, of Indianapolis, in the county of Marion and State of Indiana, have invented a new and 5 Improved Mode of Feeding Flour-Bolts; and I do hereby declare that the following is a full, clear, and exact description of the same, reference being had to the annexed drawings, making a part of this specification, in which—

Figure 1, is an end view of two flour bolts with my improvement applied to them. Fig. 2, is a vertical section of the annular chamber, and hopper boy the flight arm 15 above not being bisected. Fig. 3, is a plan or top view of the flight arm, hopper boy and annular chamber. Fig. 4, is a detached view of a portion of one of the bolts and the spout which conveys the flour from the annular chamber to the bolt.

Similar letters of reference indicate corresponding parts in the several figures.

This invention relates to a new and improved mode of feeding flour bolts whereby 25 the meal is fed at all times equally and uniformly to the bolt as will be presently shown.

To enable others skilled in the art to fully understand and construct my invention I 30 will proceed to describe it.

A, A, Fig. 1 represent the elevated ends 35 of two flour bolts, or, the ends in which the meal enters. These bolts are inclosed by a proper chest, not represented, and constructed in the usual or any other proper manner.

Directly above the two bolts A, A, there is 40 a circular platform B technically termed a "hopper-boy" in the center of which is fitted an annular chamber C, see Figs. 1, 2 and 3, provided with a cover (a) having two apertures (b) (b) in it near its edge and at opposite points to each other as shown in Figs. 2 and 3.

D is a vertical shaft which passes through 45 the center of the "hopper-boy" and annular chamber C. To the shaft D are attached sweeper arms (c) having sweepers (d) secured to their ends, said sweepers being 50 within the annular chamber C as clearly shown in Fig. 2. On the shaft D directly above the "hopper-boy" B there is placed loosely a flight arm E having flights (e) 55 secured in an oblique position to its under side as clearly shown by the dotted lines in Fig. 3.

F is a rod which passes horizontally through the shaft D and has cords (f) attached to its ends said cords being also connected to the ends of the flight arm as shown 60 in Fig. 1.

G, G, are spouts which lead from the lower part of the annular chamber C to the elevated ends of the bolts A, A, see Figs. 1 and 4. The upper ends of these spouts are 65 provided with slides (g) as shown in Figs. 1 and 2.

At the lower end of the shaft D there is a toothed wheel H which gears into a pinion I at the upper end of a shaft J, the shaft J 70 having a bevel wheel K at its lower end and which gears into a bevel wheel L on a horizontal shaft M, see Fig. 1. At each end of the horizontal shaft M, there is a bevel wheel N, these bevel wheels gear into bevel 75 wheels O, at the ends of the bolt shafts P.

Operation. The meal to be bolted falls upon the "hopper-boy" B and as the shaft D rotates motion is given the flight arm E in consequence of its attachment to the rod 80 F by the cords (f). The flights (e) as the arm E rotates carry the meal toward the center of the "hopper-boy" B and it falls through the openings (b) (b) into the annular chamber C, the meal being cooled in 85 its passage from the periphery of the "hopper-boy" to the annular chamber. The sweepers (d) (d) as they revolve force the meal from the annular chamber C into the spouts G, G, which convey it into the elevated ends of the bolts A, A.

By the above invention the meal is fed in a regular and uniform manner to the bolts and is in consequence perfectly bolted. The usual method of feeding the meal to the 95 bolts is by means of spouts with a "drop shoe" under each spout. A shake motion is given the "drop shoes" by means of cam or wiper wheels which cause the meal to slide down the incline bottoms of the drop shoes 100 whence it is conducted into the bolts through ordinary spouts. The "drop shoes" supply the bolts very irregularly with meal as the jar of the shoes condenses or packs the meal in the large spouts over them and when the 105 slides or gates are drawn a large quantity of meal rushes into the bolts which is in consequence not only imperfectly bolted, but is the cause of sending forward so much offal, returns etc. to the subsequent machinery, 110 that the elevators, conveyers and spouts are frequently choked. This difficulty is avoided

by my improvement, the feeding as previously stated being equal and uniform at all times.

I claim neither the "hopper-boy" nor the flight arm with flights attached separately for they have been previously used.

What I do claim as new and desire to secure by Letters Patent, is,

I claim the combination of the annular chamber C, with its sweepers (d) (d) as arranged for the purpose set forth. 10

SAMUEL TAGGART.
